UNITED STATES PATENT OFFICE.

ROSE PAULINE JABOULET-VERCHERRE, OF LONDON, ENGLAND.

DESIGN FOR A DOILY.

49,494.

Specification for Design. Patented Aug. 8, 1916.

Application filed May 11, 1916. Serial No. 96,933. Term of patent 7 years.

To all whom it may concern:

Be it known that I, Rose PAULINE JABOULET-VERCHERRE, a citizen of France, residing at London, England, have invented a new, original, and ornamental Design for a Doily, of which the following is a specification, reference being had to the accompanying drawing, forming part thereof.

The figure is a plan view of a doily, showing my new design.

The doily is preferably made of paper with the novel design embossed thereon. A texture A, represented by the cross-hatched lines, is embossed on the entire surface of the doily.

I claim:

The ornamental design for a doily, as shown and described.

ROSE PAULINE JABOULET-VERCHERRE.
